UNITED STATES PATENT OFFICE.

ELMER L. OUCHIE, OF NORTH TONAWANDA, NEW YORK, ASSIGNOR TO RAND KARDEX BUREAU, INC., OF TONAWANDA, NEW YORK, A CORPORATION OF DELAWARE.

FILING DEVICE.

Application filed June 15, 1925. Serial No. 37,132.

My invention relates in general to drawers for filing devices and in particular to bottom stops for card index systems of the overlapping card type in which the tongues carried 5 by the cards or card pockets are nested or interlocked when assembled.

The principal object of my invention has been to provide a bottom stop which shall be held in position by resilient means and 10 which shall firmly but flexibly hold the card pockets in their nested positions.

Another object has been to provide a bottom stop which shall not require to be locked in position but which may be operated by 15 grasping and pulling downwardly on any particular card pocket where it is desired to insert or release a card pocket.

Furthermore, my bottom stop, when once pulled back to its inoperative position will 20 be held in such position until released.

Moreover, my device is simple and inexpensive to manufacture, and is durable in operation.

The above objects and advantages have 25 been accomplished by the device shown in the accompanying drawings, in which:

Fig. 1 is a fragmentary plan view of a drawer or tray of a filing cabinet showing my invention.

Fig. 2 is a side sectional view taken on line 2—2 of Fig. 1, showing the device in its 30 normal operative position.

Fig. 3 is a similar view showing the device held back in its inoperative position.

In the drawings, the drawer is represented 35 at 5, and is of the type having guide channels 6 arranged at each side for the reception of the ends of the tongues 7 of the card pockets 8.

My invention is adapted to that type of 40 filing system in which the card pocket 8 is fastened near the upper edge to the tongue 7, leaving the space near the lower edge of the tongue for the overlapping of the tongue

45 of the lower card pocket, whereby the pockets are held with their tongues in nested relationship. In this type of filing system, it is essential that the pockets be tucked together rather firmly in order that they may 50 be held interengagingly. In order to accomplish this, I provide a bottom stop 9. This stop is provided at its inner edge with an upturned portion 10 which is designed to engage the space between the tongue 7 and 55 the pocket 8 of the lowermost pocket and to

be engaged with that portion of the upper surface of the tongue which is not attached to the pocket. This stop is preferably formed of sheet metal and at its outer end is bent upon itself and provided with a 60 downwardly extending flange 11 located some distance inwardly from the outer edge 20. A helical spring 12 has its ends engageable with the flange 11 and midway of its length it is held by a hook 13, whereby 65 the stop 9 will always be resiliently held in its normal inward position. The hook 13 is preferably a part of a stop 14, arranged near the front of the drawer with which the flange 11 of the bottom stop is engageable 70 when drawn to its outward position as shown in Fig. 3. Under normal conditions the outer edge 20 of the bottom stop 9 will lie inside of and slightly below the upper edge 16 of the front 15 of the drawer. When, 75 however, the bottom stop is drawn outwardly, it is necessary that the outer edge be raised above the level of the flange 16, and to accomplish this, I provide an inclined surface 17 which terminates in the upstanding stop lug 14 and which will engage the lower edge of the flange 11 to raise the stop as stated. If desired, the bottom stop may be provided with an opening 18 for engagement with the finger when the stop 9 is 80 moved to its outward position.

From the foregoing, it will be clear that the spring 12 will keep the bottom stop 9 pushed firmly against the tongue 7 of the lower card pocket 8 in the drawer and will 90 likewise keep each of the tongues of the series of cards in the drawer in firm contact and engagement with each other. Owing to the flexibility of the spring 12, the number of cards used in the drawer may, within 95 reasonable limits, be increased or decreased as desired.

When it is desired to remove a pocket, or to place another one in the drawer, it is only necessary that the pocket which is to 100 be removed or the one immediately below it be grasped or pulled toward the outer end of the drawer. This will push the bottom stop outwardly and the flange 11 there- 105 of will move up the inclined surface 17 until it has reached the outer end of this surface, when it will drop in front of the stop 14 and be held in this position until released. In this manner any number of pockets may be removed from or added to the tray up 110

to the limit of its capacity. When it is desired to again lock the pockets, it is only necessary that the forward edge 20 of the bottom stop 9 be slightly lifted so as to release the flange 11 from engagement with the stop lug 14, whereby the spring 12 will draw the bottom card into position on top of the tongue 7 of the lower card pocket and against the joint between the pocket and the tongue. The inner edge of the bottom stop is upturned slightly so that it will conveniently pass over the tongue of the end card pocket.

Obviously some modifications of the details herein shown and described may be made without departing from the spirit of my invention or the scope of the appended claims, and I do not, therefore, wish to be limited to the exact embodiment herein shown and described, the form shown being merely a preferred embodiment thereof.

Having thus described my invention, what I claim is:

1. In a filing device, a drawer adapted to receive a series of cards in nested position, a bottom stop adapted to yieldingly press against the end card of said series, and catch means adapted to maintain said bottom stop out of engagement with said cards

30 so as to permit the removal of a card.

2. In a filing device, a drawer adapted to receive a series of cards in nested position, a bottom stop, a helical spring connected between said bottom stop and drawer and adapted to yieldingly press said bottom stop against a card to prevent removal of said cards.

3. In a filing device, a drawer adapted to receive a series of cards in nested position, a bottom stop, a spring adapted to cause said bottom stop to yieldingly press against a card to prevent removal of said cards, and a catch adapted to hold said bottom stop out of engagement with said card against

the action of said spring so as to permit 45 removal of said cards.

4. In a filing device, a drawer adapted to receive a series of cards in nested position, a bottom stop adapted to yieldingly press against a card to prevent removal of said 50 cards, said bottom stop being adapted to be moved to card-removing position by manual actuation of a card intermediate the ends of the series of cards.

5. A filing device, the combination of a 55 drawer with a bottom stop formed with a downwardly extending flange located some distance from the outer edge of the stop, a spring having its ends attached to the flange, and a hook carried by the drawer for engagement with the middle portion of the 60 spring.

6. A filing device, the combination of a 65 drawer for the reception of cards and having a bottom stop formed with a downwardly extending flange, a stop lug secured to the drawer and engageable with the flange, the stop lug being formed with an inclined surface terminating at the outer face thereof and engageable with the flange, and flexible means secured to the drawer for holding the bottom stop in its card-engaging 70 position.

7. A filing device, the combination of a 75 drawer with a bottom stop formed with a downwardly extending flange located some distance from the outer edge of the stop, a stop lug secured to the drawer and engageable with the flange, and the stop lug being formed with an inclined surface terminating at the outer face thereof and engageable with the flange, a spring having its ends attached to the flange, and a hook carried by the drawer for engagement with the middle portion of the flange.

In testimony whereof, I have hereunto signed my name.

ELMER L. OUCHIE.
